(57) **CLAIM**

(21) Appl. No.: **29/148,087**

The ornamental design for a illuminated alphanumeric character display, as shown and described.

(22) Filed: **Sep. 14, 2001**

DESCRIPTION

(51) LOC (7) Cl. **20-03**

FIG. 1 is a front elevational view of a illuminated alphanumeric character display showing my new design;

(52) U.S. Cl. **D20/17**

FIG. 2 is a rear elevational view thereof;

(58) Field of Search D20/10, 17, 18,
D20/19; D26/31; 40/431, 441, 542, 544,
545, 547, 551, 568, 569, 570, 572, 573

FIG. 3 is a left side view, the right side being a mirror image

thereof;

FIG. 4 is a top plan view thereof; and,

FIG. 5 is a bottom plan view thereof.

In the drawings, the broken line showing of numbering is for
illustrative purposes only and forms no part of the claimed
design.
